Samuel Mueller, Maplewood, N. J., assignor to
C. F. Mueller Company, Hudson County, N. J., a corporation of New Jersey

Application September 12, 1947, Serial No. 141,363

Term of patent 14 years

(Cl. D8—1)

To all whom it may concern:

Be it known that I, Samuel Mueller, a citizen of the United States of America, residing at Maplewood, Essex County, State of New Jersey, have invented a new, original, and ornamental Design for a Noodle or Similar Article, of which the following is a specification, reference being had to the accompanying drawing, forming part thereof.

In the drawing:

Fig. 1 is a top plan view of a noodle or similar article, showing my new design;

Fig. 2 is a side elevation of Fig. 1;

Fig. 3 is an end elevational view of Fig. 1; and

Fig. 4 is a perspective view of the product.

I claim:

The ornamental design for a noodle or similar article, substantially as shown.

SAMUEL MUELLER.
